APPARATUS FOR POLISHING AND CLEANING PLASTIC ARTICLES

Lawrence G. Hileman, Jonesboro, Ind., and Stephen T. Moreland and Joseph B. Potocsky, Toledo, Ohio, assignors to Owens-Illinois Glass Company, a corporation of Ohio

Application April 7, 1939, Serial No. 266,650

4 Claims. (Cl. 51—164)

The present invention relates to cleaning and polishing apparatus and more particularly to an apparatus for removing flash from articles which have been molded from plastic materials and for 5 polishing the articles preparatory to packaging the same.

The cleaning and polishing apparatus comprising the present invention is primarily designed for use in removing the flash from relatively small plastic articles as, for example, bottle caps which are received by the apparatus direct from the molds of a forming machine while the articles are still hot. Thus, by the use of the apparatus, not only is the flash removed and the 10 articles polished but the articles are, in passing through the apparatus, given time to cool in order that they may be packaged immediately after they have been discharged from the apparatus.

20 The principal object of the invention is to provide an apparatus of the character set forth above, which is relatively simple in its construction and which is possessed of a minimum number of moving parts, thus rendering the apparatus rugged and durable and consequently unlikely to get out of order.

Another object of the invention is to provide such an apparatus which, considering the size thereof, is capable of handling a relatively large 30 number of the articles at one time either by a flow of the articles therethrough or by the introduction of batches periodically thereinto.

Other objects and advantages of the invention, not at this time enumerated, will become 35 apparent as the nature of the invention is better understood.

In the accompanying drawings:

Fig. 1 is a side elevational view, partly in section, of a polishing and cleaning apparatus constructed in accordance with the principles of the present invention;

Fig. 2 is a sectional view taken substantially along the line 2—2 of Fig. 1;

Fig. 3 is an enlarged fragmentary sectional view taken through the apparatus on a vertical plane;

Fig. 4 is a sectional view taken substantially along the line 4—4 of Fig. 3;

Fig. 5 is a sectional view taken substantially 50 along the line 5—5 of Fig. 1;

Fig. 6 is a sectional view similar to Fig. 3 showing a modified form of the invention; and

Fig. 7 is a sectional view taken substantially 55 along the line 7—7 of Fig. 6.

The apparatus involves in its general organization a wheeled frame or carrier 10 (Figs. 1 and 2) including front and rear supporting legs 11 and 12 respectively which are connected together in the lower regions thereof by means of longitudinal and transverse cross-pieces 13 and 14

respectively. Transverse cross-pieces 15 extend across the upper ends of each adjacent pair of front and rear legs.

Pivoted at opposite sides of the frame 10 to a pair of brackets 9 mounted on the front legs 11 is a tiltable platform 16 including generally triangular side pieces 17 and a top 18. Bolt and slot connections 19 between the side plates 17 and a pair of brackets 20 secured to the rear legs 12 permit the inclination of the platform 16 to be adjusted for a purpose subsequently to appear.

Bolted or otherwise secured to the top 18 of the platform 16 adjacent the forward end thereof is a pair of bifurcated brackets 21. A similar pair of brackets 22 is secured to the top 18 adjacent the rear end thereof. A roller 23 is suspended between the bifurcations of each bracket, the four rollers 23 providing in effect a cradle upon which is rotatably supported a hollow open-ended cylindrical tumbler barrel 24.

The tumbler barrel 24 (Figs. 3 and 4) is preferably formed of relatively light gauge sheet metal and is perforated as at 25. A hoop or ring 26 extends around and is secured to the barrel 24 at the forward end thereof and is grooved as at 27 for tractional support on the rollers 23 carried by the brackets 21. A similar hoop or ring 28 extends around and is secured to the barrel at the rear end thereof and is grooved as at 29 for tractional support on the rollers 23 carried by the brackets 22. The barrel 24 is thus loosely and tractionally supported on the cradle provided by the rollers 23. A second groove 30 is formed in the ring 28 for the reception of a driving belt 31 which passes over a pulley 32 mounted on the driving shaft 33 of an electric motor M adjustably secured by bolt and slot connections 34 to one of the side plates 17 of the platform 16.

Secured to the inside of the barrel 24 in such a manner as not to block the perforations 25 therein is a plurality of longitudinally extending ribs 35 which extend from the forward edge of the barrel to the medial regions thereof. A similar series of ribs 36 extends from the rear edge of the barrel and meets the strips 35 in end-to-end relationship. A circular baffle plate 37 is centered in the barrel and extends transversely thereof medially of the ribs 35, it being secured in position by means of brackets 38. A ring-like baffle 39 extends transversely of the barrel medially thereof and is secured in place by brackets 40. A second circular baffle 41 similar to the baffle 37 is secured in position by brackets 42 medially of the ribs 36.

Referring now to Fig. 4, the ribs 36 are provided with longitudinal dove-tail slots 43 therein in which are slidably and removably received a plurality of polishing brush units 44. The brush

units 44 occupy positions in close proximity to each other and provide in effect a polishing brush lining for the interior of the barrel 24 covering the entire rear half thereof.

5 Referring now to Fig. 3, an apron 45 is secured to the hoop or ring 26 and is provided with a central opening 46 through which the bottle caps or other plastic articles may be introduced to the barrel. A casing 47 is secured to the frame 10 or carrier 10 near the bottom of the apparatus and is provided with hinged sections 48 to facilitate inspection or adjustment of the barrel 24. The apron 45 projects through an opening 49 in the casing 47 at the forward side of the apparatus. A portion of the casing 47 at the rear side thereof is offset as at 50 to provide a clearance for the bottle caps or other plastic articles issuing from the barrel 24 at the rear thereof. The bottle caps or other articles are projected against this offset portion 50 and fall by gravity through an opening 51 and are thus discharged from the apparatus.

10 The top 18 of the platform 16 is provided with a central opening 52 therein (Fig. 3) through which flash removed from the bottle caps or other articles falls by gravity and is received in a drawer 53 supported therebeneath on the transverse cross-pieces 13.

15 In the operation of the apparatus, the bottle caps or other articles are introduced into the rotating barrel 24 at the forward end thereof through the opening 46 in the apron 45 and fall by gravity onto the ribs 35 by means of which they are caused to tumble haphazardly in the space existing between the baffle 37 and the forward end of the barrel. While so tumbling, the caps flow generally toward the rear of the barrel, passing beneath the baffle 37 and over the ring-like baffle 39 and into contact with the brush units 44. While in the forward region of the barrel, the caps come forcibly into repeated contact with the ribs 35 and into contact with each other and the relatively fragile flash existing on the same is broken off and falls through the perforations 25 and is received in the drawer 53. After the caps have moved into the rear region of the barrel, they are effectively polished by means of the brush units 44 with which they come into repeated contact and, after passing 20 under the baffle 41 they are ejected through the opening 51.

25 In the modified form of barrel construction shown in Figs. 6 and 7, the internal longitudinally extending ribs 35 and 36 have been omitted and no provision is made for polishing the caps or other articles by a brushing operation. A series of agitating members 60 in the form of ribs that are triangular in cross-section extends from the forward edge of the barrel 24' rearwardly a short distance and insures adequate and forcible agitation of the bottle caps or other articles at the outset. A series of spiral vanes 61 extends from the rear edge of the barrel 24' forwardly a short distance and, in addition, to additionally 30 agitate the articles, assists in impelling the articles toward the discharge opening 51'.

35 It is to be noted that the rate of travel of the articles through the barrel in either form of the invention may be controlled by adjusting the inclination of the platform.

40 Modifications may be resorted to within the spirit and scope of the appended claims.

We claim:

45 1. In an apparatus for removing flash from

articles which have been molded from plastic materials, an open ended barrel adapted to receive therein through one open end the articles to be treated and to discharge the treated articles from the other end thereof, there being perforations in the wall of the barrel through which flash removed from the articles is adapted to pass by gravity, a baffle ring secured at its outer periphery to the wall of the barrel medially thereof and over which the articles are adapted to flow in passing from the receiving end to the discharge end of the barrel, and means for rotating the barrel about a substantially horizontal axis.

50 2. In an apparatus for removing flash from articles which have been molded from plastic materials, an open ended barrel adapted to receive therein through one open end the articles to be treated and to discharge the treated articles from the other end thereof, there being perforations in the wall of the barrel through which flash removed from the articles is adapted to pass by gravity, a baffle ring secured at its periphery to the wall of the barrel medially thereof and over which the articles are adapted to flow in passing from the receiving end to the discharge end of the barrel, a baffle plate disposed in the barrel and having its periphery spaced from the wall of the barrel and around which articles are adapted to pass in passing from the receiving end to the discharge end of the barrel, and means for rotating the barrel about a substantially horizontal axis.

55 3. In an apparatus for removing flash from articles which have been molded from plastic materials, an open ended barrel adapted to receive therein through one open end the articles to be treated and to discharge the treated articles from the other end thereof, there being perforations in the wall of the barrel through which flash removed from the articles is adapted to pass by gravity, a baffle ring secured at its outer periphery to the wall of the barrel medially thereof and over which the articles are adapted to flow in passing from the receiving end to the discharge end of the barrel, means for rotating the barrel about a substantially horizontal axis, and a plurality of polishing brushes projecting radially inward from the wall of the barrel rearwardly of said baffle ring.

60 4. In an apparatus for removing flash from articles which have been molded from plastic materials, an open ended barrel adapted to receive therein through one open end the articles to be treated and to discharge the treated articles from the other end thereof, there being perforations in the wall of the barrel through which flash removed from the articles is adapted to pass by gravity, a baffle ring secured at its periphery to the wall of the barrel medially thereof and over which the articles are adapted to flow in passing from the receiving end to the discharge end of the barrel, a baffle plate disposed in the barrel and having its periphery spaced from the wall of the barrel and around which articles are adapted to pass in passing from the receiving end to the discharge end of the barrel, means for rotating the barrel about a substantially horizontal axis, and a plurality of polishing brushes projecting radially inward from the wall of the barrel rearwardly of said baffle ring.
